Primary Examiner — Jack Reickel*Assistant Examiner* — Bobby W Jones, II(74) *Attorney, Agent, or Firm* — Mark C. Johnson;
Johnson Dalal(57) **CLAIM**

The ornamental design for a vent cover, as shown and described.

DESCRIPTION

FIG. 1 is a top perspective view of a vent cover in accordance with the present invention;

FIG. 2 is an elevational left-side view, the right-side being a mirror image thereof, of the vent cover in FIG. 1;

FIG. 3 is a front elevational view, of the vent cover in FIG. 1;

FIG. 4 is a rear elevational view of the vent cover in FIG. 1; and,

FIG. 5 is a top plan view of the vent cover in FIG. 1.
